UNITED STATES PATENT OFFICE

JOSEPH E. JOHNSTON, OF DES MOINES, IOWA

DESIGN FOR A COMBINED TALLY DEVICE AND ASH TRAY

Application filed March 16, 1931. Serial No. 39,098. Term of patent 3½ years.

To all whom it may concern:

Be it known that I, JOSEPH E. JOHNSTON, a citizen of the United States, and a resident of Des Moines, in the county of Polk and State of Iowa, have invented a new, original, and ornamental Design for a Combined Tally Device and Ash Tray, of which the following is a specification, reference being had to the accompanying drawings forming part thereof.

Figure 1 is a perspective view of the front

and one side; and Figure 2 is a perspective view of the rear and the opposite side of a combined tally device and ash tray, showing my new design.

I claim:

The ornamental design for a combined tally device and ash tray, as shown.

Des Moines, Iowa, March 3, 1931.

JOSEPH E. JOHNSTON.
